United States Patent Office

Des. 180,878
Patented Aug. 27, 1957

180,878

SPOON OR SIMILAR ARTICLE

Richard Seamon Latham, Chicago, Ill., assignor to Ekco Products Company, Chicago, Ill., a corporation of Illinois

Application March 15, 1956, Serial No. 40,628

Term of patent 14 years

(Cl. D44—29)

Fig. 1 is a front elevational view of a spoon or similar article, showing my new design.

Fig. 2 is a side elevational view thereof.

Fig. 3 is an enlarged rear end view thereof.

Fig. 4 is an enlarged sectional view taken on line 4—4 of Fig. 1.

The essential features of my design reside in the contour of the handle and the ornamentation applied thereto by means of a pair of rivets located in spaced apart relation lengthwise of the handle and arranged symmetrically of an area of the handle extending rearwardly from the forward end of the handle a distance approximately half the length of the handle and a hanging eyelet located midway of the distance between said rivets.

I claim:

The ornamental design for a spoon or similar article, as shown and described.
